Patented Aug. 15, 1922.

3 SHEETS—SHEET 3.

This technical drawing illustrates a mechanical assembly, possibly a conveyor system, featuring a central vertical frame and various components. Key parts include:

- Horizontal bars: 60, 61, 62, 63, 64, 65, 66.
- Vertical supports: 10, 12, 16, 18, 20, 22, 24, 26, 28, 30, 32, 34, 36, 38, 40, 42, 44, 46, 48, 50, 52, 54, 56, 58, 60, 62, 64, 66.
- Shafts: 15, 17, 19, 21, 23, 25, 27, 29, 31, 33, 35, 37, 39, 41, 43, 45, 47, 49, 51, 53, 55, 57, 59, 61, 63, 65, 67, 69, 71.
- Wheels: 11, 13, 15, 17, 19, 21, 23, 25, 27, 29, 31, 33, 35, 37, 39, 41, 43, 45, 47, 49, 51, 53, 55, 57, 59, 61, 63, 65, 67, 69, 71.
- Belts: 12, 14, 16, 18, 20, 22, 24, 26, 28, 30, 32, 34, 36, 38, 40, 42, 44, 46, 48, 50, 52, 54, 56, 58, 60, 62, 64, 66.

UNITED STATES PATENT OFFICE.

CHARLES E. CHAPMAN, OF CHICAGO, ILLINOIS.

MOVING DISPLAY APPARATUS FOR JEWELRY.

1,425,508.

Specification of Letters Patent Patented Aug. 15, 1922.

Application filed September 17, 1921. Serial No. 501,370.

To all whom it may concern:

Be it known that I, CHARLES E. CHAPMAN, a citizen of the United States, residing at Chicago, in the county of Cook and State of Illinois, have invented certain new and useful Improvements in a Moving Display Apparatus for Jewelry, of which the following is a specification.

This invention relates generally to improvements in apparatus for exhibiting or displaying merchandise, but has particular relation to a device to be used for movably displaying in the show cases or show windows of jewelry stores, that type of pieces of jewelry which carry or have mounted thereon brilliant settings, gems, precious stones, or imitations thereof, for instance, finger rings, ear-rings, brooches, scarf-pins, hair ornaments, and the like, and it consists 10 in certain peculiarities of the construction, novel arrangement and combination of the various parts thereof as will be hereinafter more fully set forth and specifically claimed.

The principal object of the invention is to 25 provide an apparatus of the above mentioned general character, whereby one or more platforms or tables thereof, on which pieces of jewelry are mounted, will be automatically tilted towards and from the observer or prospective purchaser, to the end, that the settings of the pieces of jewelry will 30 be subjected to the rays of light at varying angles, thereby causing the stones or settings to scintillate, flash or sparkle and to otherwise better display their beauty or attractiveness.

Another object is to provide a display apparatus of such construction and arrangement of its parts, that a plurality of trays, 40 each having a plurality of tilttable platforms on which pieces of jewelry may be mounted, can be operatively disposed on the main or supporting frame of the apparatus in such a way that they can be handled as a unit, 45 and so that their respective sets of platforms will be tilted successively in pairs, by the same motive power.

A further object is to so make the apparatus that its operative mechanism will be 50 self-contained and invisible to customers, yet simple and inexpensive in construction, strong, durable and efficient in operation.

Other objects and advantages of the invention will be disclosed in the following 55 description and explanation.

In the accompanying drawings, which

serve to illustrate an embodiment of the invention—

Fig. 1 is a perspective view of an apparatus constructed according to the invention 60 showing the movable parts thereof in some of the positions they will assume in the operation of the apparatus and illustrating a pair of cards each carrying a piece of jewelry mounted on the tilttable platforms 65 of the apparatus.

Fig. 2 is an enlarged plan view showing portions of the trays which carry the tilttable platforms broken away to illustrate the driving mechanism for said platforms. In 70 this view the tilttable platforms are shown in the same positions as that occupied by them in Fig. 1.

Fig. 3 is a cross-sectional view taken on line 3—3 of Fig. 2 looking in the direction 75 indicated by the arrows.

Fig. 4 is an enlarged plan view of a train of gears and its housing, used for transmitting power from the motor to the driving shaft of the apparatus.

Fig. 5 is an enlarged view partly in section and partly in elevation of one of the lifting rods of the device for the tilttable platforms, and

Fig. 6 is a detail view of one of the tilttable 85 platforms showing the manner of mounting the same and of mounting a jewelry carrying card thereon.

Corresponding numerals of reference refer to like parts throughout the different views 90 of the drawings.

Referring now more particularly to Figs. 1 to 3 inclusive of the drawings, the reference numeral 10 designates the main or supporting frame of the apparatus, which frame 95 may be made of any suitable size, form and material but preferably of wood or metal and of an elongated rectangular shape as shown. The end pieces 11 of this frame are united near their upper edges and about 100 midway between the sides 12 of the frame by means of a longitudinally and horizontally disposed bar 13, which bar may have its ends fastened to the inner surfaces of the end pieces 11 by any suitable and secure 105 means. Located on top of the bar 13 and extended longitudinally thereon from one of the end pieces 11 of the main frame to the other end piece thereof, is a cleat 14 on the upper surface of which rests the stationary 110 floor or platform 15 of the frame, the edges of which lie and are suitably secured in ver-

tically disposed recesses or rabbets 16 located in the upper edges of the supporting frame as will be clearly understood by reference to Fig. 3 of the drawings. This floor 5 or platform may be covered with felt, plush or any other suitable covering, not shown. The end pieces 11 of the main frame are also united about midway between the side pieces 12 of said frame by means of a longitudinally extended bar 17 on the upper surface of which is mounted the inner end of a floor 18 the outer end of which is mounted on a horizontally and longitudinally disposed bar 19 secured on the inner surface of one of the 10 side pieces 12 of the main frame at the lower edge thereof. The floor 18 has mounted on its upper surface near its inner end an upright bracket 20 which carries an idle roller or pulley 21 for the purpose to be presently 15 explained. Extended transversely with respect to the main frame 10 near the upper edge thereof, are a plurality of spaced horizontally disposed bars 22 which rest at their middle portions on the upper surface of the 20 longitudinally disposed bar 13 and are suitably secured at their ends to the inner surfaces of the side pieces 12 of the main frame. These bars 22 assist in supporting the floor 25 of the main frame and each of them is 25 provided with a pair of vertical openings located one on each side of the bar 13 about midway between said bar and the sides of the frame.

Each of the openings in each of the bars 30 22 has fitted therein a tubular extension 23 on the lower surface of a grease cup or receptacle 24, which cups and extensions are preferably made of metal. The extension 23 of each cup is extended through a suitable 35 opening in the floor 15, which opening registers with one of the openings in the transverse bars 22. By reference to Fig. 2 of the drawings, it will be seen that the cups 24 are annular in shape and may be imbedded 40 in the floor 15 as shown so as to surround the openings in which the extensions 23 are located so as to more securely hold said cups in position.

Longitudinally journaled in the end 45 pieces 11 of the main frame at one side of the bar 13 and in parallelism therewith, is a shaft 25, on which is mounted to turn therewith a pulley 26, which is by preference of the peripherally grooved type. Fixed on the 50 shaft 25 directly below each of the transverse bars 22 is an eccentric disk or cam.

Referring now to Figs. 2 and 3 of the drawings, it will be understood that the eccentric disk designated by the numeral 27, 55 is located under the bar 22 adjacent the left hand end of the main frame of the apparatus, and that the disk 28 is located under the bar 22 at the middle of the main frame, while the disk or eccentric 29 is located under the transverse bar 22 near the right hand

end of the main frame. It will also be seen in Fig. 3 that these eccentrics or disks are so mounted on the shaft 25 as to present their greatest eccentricity in the rotation of the shaft 25 at different intervals, thereby 70 causing the levers with which they contact to be elevated and lowered successfully.

Mounted on the floor 18 of the main frame near one of the sides of said frame is an electric motor 30 of the ordinary or any preferred construction, which may be connected to a source of electric supply in an ordinary or well known manner. Mounted on the floor 18 near one end of the motor 30 is a gear casing 31 in which is transversely journaled a shaft 32 which carries on one of its ends a grooved pulley 33, and within the casing 31 a pinion 34. The grooved pulley 33 is geared to the shaft 35 of the motor by means of a belt 36 which 80 passes over the pulley 33 and a pulley 37 on the end of the motor shaft 35 adjacent the gear casing. The pinion 34 meshes with a gear 38 mounted on a shaft 39 transversely journaled in the casing 31, which shaft has 90 mounted thereon a pinion 40 in mesh with a gear 41 mounted on a shaft 42 transversely journaled in the casing 31 as is clearly shown in Fig. 4 of the drawings. This last named shaft has mounted thereon outwardly 95 of the gear casing 31 and on the opposite side thereof from the motor, a grooved pulley 43 over which is extended a belt 44, which belt also extends around the pulley 26 of the driven shaft of the apparatus. By 100 reference to Figs. 2 and 3 of the drawings, it will be seen that the belt 44 is adapted to rest on the idle pulley 21 so that undue slackness of said belt may be taken up or compensated for.

Secured to the lower surface of the bar 13 and depending therefrom under each of the transverse bars 22 is a bracket 45, (see Fig. 3) to the lower portion of each of which is pivotally secured at about its middle, a 110 lever 46 each of which levers is located directly under one of the transverse bars 22 and is adapted to be moved in a vertical plane thereunder, by means of the eccentrics 27, 28, and 29, on which the levers 46 rest 115 near one of their ends. Each of the levers 46 is provided at its end adjacent its co-acting eccentric with a weight 47 which are employed to constantly hold said levers in contact with their respective eccentrics.

Pivots connected at one of its ends to each of the levers 46 near the weighted end thereof is a link 48, the other end of each of which is pivotally connected to the lower end of a lifting rod or plunger 49, which 125 plungers are extended through the tubular extensions 23 of the grease cups 24 located on that portion of the floor 15 of the main frame above the weighted ends of said levers.

Pivots connected at one of its ends to 130

the opposite end of each of the levers 46 is another link 48 each of which is pivotally connected at its other end to a lifting rod or plunger 49 extended through the tubular extensions 23 of the grease cups 24 located on that side of the bar 13 opposite the first mentioned grease cups. Each of the lifting rods 49 has its upper end rounded as at 50, and is provided with a channel or bore 51 extended from its upper end downwardly a suitable distance and then laterally as at 52, see Fig. 5, so as to provide means for the passage of a lubricant to the tubular extensions 23 in which the lifting rods operate.

Each of the levers 46 is provided above the eccentric on which it rests with a grease cup 53 having an outlet through its lever for depositing lubricant on its supporting eccentric.

Mounted on the floor 15 of the main or supporting frame are a plurality, usually 6, of rectangularly shaped frame-like trays which are designated by the numerals 54, 55, 56, 57, 58, and 59. These trays, as is clearly shown in Figs. 1 and 2 of the drawings, are located in pairs transversely of the main frame, that is to say, the trays 54, and 55, constitute one pair of trays, 56 and 57, another pair, and the trays 58 and 59 a third pair. Each of these trays has a plurality of platforms 60 pivotally mounted at one of their longitudinal edges on spaced rods 61 secured in parallelism with one another on the end pieces of the tray. Each of these platforms is provided at one of its ends with an upturned lug 62, which lugs on the set of platforms located in one of the trays, are loosely connected together by means of a bar 63 pivoted to said lugs. Each of these platforms 60 is preferably pivotally secured on one of the supporting rods 61 therefor by means of a flange 64 which is bent upwardly and then towards the upper surface of the platform so as to loosely receive its supporting rod 61. These flanges 64 not only serve to pivotally secure the platforms 60 on their respective supporting rods 61, but also serve the purpose of engaging and holding the lower portions of cards 65 on the upper portions of which a piece of jewelry 66 may be mounted in the ordinary way. These cards may be located on the upper surface of the platforms 60 with their lower edges interposed between the flanges 64 and the body of the platforms, as will be readily understood by reference to Fig. 6 of the drawings.

By connecting each set of the platforms 60, that is to say, the platforms located in each of the trays at one of their ends by means of the bars 63 and lugs 62, it is apparent that any movement of any one platform of a set will cause the other platforms of said set to move in a corresponding direction. As these platforms are connected in

sets by the bars 63 which are located above the supporting rods 61 for said platforms, it is manifest that the downward movement of said platforms will be restricted to horizontal positions as shown in the left hand corner of Fig. 1 and the left hand portion of Fig. 3 of the drawings, while their movements in an upward direction will be limited to that of the upward strokes or movements of the lifting rods 49 which impinge against the lower surface of the intermediate platform of each set.

From the foregoing, and by reference to the drawings, it will be readily understood and clearly seen, assuming that the parts are in the positions shown in Figs. 1 to 3 inclusive of the drawings, and that it is desired to start the apparatus for movable operation, it is only necessary to turn on the electric current to the motor 30, which will thereby be set in operation, thus causing the shaft 25, through the instrumentality of the gearing connecting it and the motor to be driven, when, by reason of the position of the eccentrics 27, 28 and 29, on said shaft, the levers 46 will be tilted in such a way as to cause the sets of platforms in the transversely disposed pairs of trays to be alternately raised and lowered.

Having thus fully described my invention, what I claim as new and desire to secure by Letters Patent is:—

1. In a display apparatus of the class described, the combination with a supporting frame, of a lever mounted therein for oscillation in a vertical plane, a plurality of display platforms horizontally and tiltably mounted side by side on said frame crosswise of and above said lever for unitary movement, means carried by the lever and separably co-acting with one of said platforms to tilt the same upwardly and means to oscillate the lever.

2. In a display apparatus of the class described, the combination with a supporting frame, of a lever mounted therein for oscillation in a vertical plane, a driven shaft journaled in said frame transversely to and below the lever, an eccentric on said shaft contacting with said lever, a plurality of display platforms horizontally and tiltably mounted side by side on said frame above said lever for unitary movement, and means carried by the lever and co-acting with one of said platforms to tilt the same upwardly.

3. In a display apparatus of the class described, the combination with a supporting frame, of a lever mounted therein for oscillation in a vertical plane, a driven shaft journaled in said frame transversely to and below the lever, an eccentric on said shaft contacting with said lever, a plurality of display platforms horizontally and tiltably mounted side by side on said frame above

the lever, a connection transversely and loosely uniting said platforms for unitary movement of the same, and means carried by the lever and co-acting with one of said platforms to tilt the same upwardly.

4. In a display apparatus of the class described, the combination with a supporting frame, of a lever mounted therein for oscillation in a vertical plane, means to oscillate said lever, a display platform horizontally and tiltably mounted on said frame above the said lever transversely with respect thereto on one side of its fulcrum, another display platform horizontally and tiltably mounted on said frame above said lever transversely with respect thereto on the opposite side of its fulcrum, means carried by the lever on each side of its fulcrum and co-acting with said platforms whereby the same will be alternately tilted upwardly.

5. In a display apparatus of the class described, the combination with a supporting frame, of a lever mounted therein for oscillation in a vertical plane, means to oscillate said lever, a set or plurality of display platforms horizontally and tiltably mounted side by side on said frame above said lever transversely with respect thereto on one side of its fulcrum, means transversely and loosely uniting the platforms of said set for unitary movement of the same, another set or plurality of display platforms horizontally and tiltably mounted side by side on said frame above the said lever transversely with respect thereto on the opposite side of its fulcrum, means transversely and loosely uniting the platforms of the last named set for unitary movement of the same, means carried by the lever on each side of its fulcrum and co-acting with one of the platforms of each set thereof whereby the said sets of platforms will be alternately tilted upwardly.

45. 6. In a display apparatus of the class described, the combination with a supporting

frame, of a lever mounted thereon for oscillation in a vertical plane, means to oscillate said lever, a pair of trays mounted on the frame above said lever, a set of display platforms horizontally and tiltably mounted side by side in each of said trays, means transversely uniting the platforms of each set for unitary movement of the same, means carried by the lever on each side of its fulcrum and co-acting with one of the platforms of each set thereof whereby the said sets of platforms will be alternately tilted upwardly.

7. In a display apparatus of the class described, the combination with a supporting frame, of a plurality of spaced parallel levers mounted therein for oscillation in vertical planes, means to oscillate said levers one after another, a set of display platforms horizontally and tiltably mounted side by side on said frame above each of the levers and on each side of the fulcrums thereof, means carried by each of the levers on each side of its fulcrum and co-acting with one of the platforms of each set thereof whereby the said sets or platforms will be alternately tilted upwardly in pairs and in sequence.

8. In a display apparatus of the class described, the combination with a supporting frame, of a plurality of spaced parallel levers mounted therein for oscillation in vertical planes, means to oscillate said levers one after another, a pair of trays mounted on the frame above each of said levers, a set of display platforms horizontally and tiltably mounted side by side in each of said trays, means transversely uniting the platforms of each set for unitary movement of the same, means carried by each of the levers on each side of its fulcrum and co-acting with one of the platforms of each pair of sets thereof whereby the sets of platforms of each pair will be alternately tilted upwardly.

CHARLES E. CHAPMAN.
